COMBINED CLOCK, LAMP, AND VASE

Frank R. Perry, Los Angeles, Calif.

Application April 13, 1951, Serial No. 14,814

Term of patent 3½ years

(Cl. D42—7)

To all whom it may concern:

Be it known that I, Frank R. Perry, a citizen of the United States of America and resident of Los Angeles, county of Los Angeles, State of California, have invented a new, original, and ornamental Design for a Combined Clock, Lamp and Vase, of which the following is a specification, reference being had to the accompanying drawing forming a part thereof, in which:

Fig. 1 is a plan view of a combined clock, lamp and vase, showing my new design;

Fig. 2 is a front elevational view of the disclosure in Fig. 1;

Fig. 3 is an end elevational view looking toward the right of Fig. 2;

Fig. 4 is an elevational view of the opposite end shown in Fig. 3;

Fig. 5 is a rear elevational view; and

Fig. 6 is a vertical fragmentary view taken on line 6—6 of Fig. 3.

I claim:

The ornamental design for a combined clock, lamp, and vase, substantially as shown,

FRANK R. PERRY.
